COMBINATION STOP MECHANISM FOR ORGANS AND THE LIKE.

Application filed June 4, 1925. Serial No. 34,971.

"Combination stop actions" are those means, usually incorporated in instruments of the pipe organ type, which are so correlated with the stop keys and stops as to 5 permit a setting of the stops into one or more selected combinations each of which is thereafter governed by a controlling member corresponding thereto.

This invention aims generally to improve 10 the mechanisms hitherto proposed for this purpose in various material respects. One of the particular objects is to provide, in a mechanism in which any one or more of the stop keys may be set to come "on" while 15 other stop keys are set to go "off" when a predetermined combination operating element is actuated, a correlation of parts which additionally permits any one of the stop keys to be set into such relation to any one 20 of the combination operating elements as to be unaffected by the actuation of the latter. In other words, it is particularly an object of 25 the invention to provide a combination stop mechanism wherein any one of the stops may be set to "on" position, to "off" position or to a "neutral" position with relation to any one of the combination operating elements.

The term "stop" as herein used comprehends a graduated group or set of pipes or other elements emitting tones having the same tonal quality, or a tremulant, coupler etc. together with the "stop keys" and connections between the respective stop keys and 35 the corresponding set or group of tone emitting elements, swell shutters, etc. for controlling the operation of the latter by said keys.

Recognizing that the main features of the 40 invention may be variously embodied I have shown three different embodiments, but wish it understood that these are merely exemplary and that changes in details may be made without departing from the spirit of 45 the invention as defined by appended claims.

In the accompanying drawings wherein like characters of reference denote corresponding parts in the several views:—

Fig. 1 is a view partly in perspective and 50 partly in section showing a part of one form of a combination stop action constructed in accordance with my invention.

Figs. 2, 3 and 4 are detail views, partly in

elevation and partly in vertical section, particularly intended to show a combination 55 operating element and its power means in three different positions, namely: when in "off" position, Fig. 2; when in "on" position, Fig. 3; and while a setting is being made, Fig. 4.

Fig. 5 is a detail view showing one suitable embodiment in which the combination operating elements are operated directly by hand pressure instead of through the medium of a manually controlled power means of electro-pneumatic nature.

Fig. 6 is a section on the line 6—6 of Fig. 5.

Figs. 7 and 8 are detail views illustrative of a further typical embodiment; Fig. 7 being a view partly in elevation with a part of a front board broken away, and partly in vertical section, and Fig. 8 being a vertical section on the line 8—8 of Fig. 7.

Fig. 9 is a detail view particularly intended to illustrate a suitable form of connecting means between a manually operable controlling means and its corresponding combination operating element, the connection illustrated being adaptable to different embodiments of the invention typified by Figs. 5—8, inclusive.

Figs. 10, 11 and 12 are detail views showing the relation of certain elements and indicative of the relation thereto of certain other 85 elements, with respect to three different typical combinations for which the parts have been set, respectively, and after they have been operated for playing purposes.

The particular embodiments hereinbefore referred to will be described in detail, without, however, intending thereby to restrict the invention thereto.

In all the figures of the drawings, 10—14 inclusive, designate stop keys which may be 95 of any suitable kind, the ones illustrated being the pivoted tablets now preferred for use in the modern pipe organ. These stop keys are individually pivoted upon a common stationary shaft 15 so as to be severally 100 movable about the shaft into "on" or "off" position, by the organist. They govern communication of the sets or groups of tone emitting elements, couplers, swells etc., respectively, with the wind system of the organ, it being understood in this connection 105

that when the outer end of any tablet is depressed to its "on" position the particular stop controlled thereby is operative and that when the outer end of said tablet is raised 5 to its "off" position the particular stop controlled thereby is inoperative.

Since the tone emitting elements, couplers, swells etc., through which they have communication with the wind system of the organ and the means operable under control 10 of the stop keys to control said means of communication form no part of the present invention and are well known in the art, they have not been herein illustrated and need 15 not be particularly described.

Each stop key is provided, as usual, with a spring *a* (shown best in Fig. 6) operatively related thereto to throw the key to either its "on" or "off" position when it has passed a 20 position midway between the two, these springs thereby operating to hold the keys against accidental displacement from their set positions, either "on" or "off".

It will, of course, be understood that the 25 number of stops and stop keys varies in different organs and that each stop included in the organ will have its appropriate stop key, and, further, that wherever the term stop or stop keys is used herein, it is intended 30 to include not only those stops which have reference to speaking pipes or tone emitting elements, but also to the mechanical stops, as swells, couplers etc., which may be incorporated in the instrument.

35 As already stated, this invention has to do with certain improvements in the mechanisms hitherto proposed by which one or more different combinations of stops may be prepared by the organist and severally 40 brought into operation, during the playing of a composition, by the actuation of the corresponding combination operating element, respectively predetermined for the purpose in the preparation or setting of the 45 combinations.

50 A series of shafts 16 corresponding to the respective stop keys have their outer ends suitably connected to the inner ends of the latter, the means shown for this purpose 55 comprising cranks 17 and links 18. Each of these shafts is provided along its length with a series of actuators B, each comprising two complementary members, marked 19 and 20, respectively. One member, as 19, of each actuating element is fixed on its shaft 16 and the other member, 20, is supported by said shaft and has pivotal movement relatively thereto.

60 Each of these actuators also has at each of its ends a means operative automatically to releasably lock their corresponding ends to each other when said ends have been brought into juxtaposition. A suitable means for this purpose comprises complementary 65 cup-shaped recesses and projections formed

on each end of the respective members 19 and 20 and adapted to interengage when brought into registration with each other by relative movement of said members. Such locking or fastening means are indicated at *b*, *b'* in 70 the drawings. It is preferred in practice that each member 19 be composed of two sides spaced from each other to receive the complementary member 20 between them. Attention is called to the fact that the members 19 and 20 of each actuator are relatively 75 so shaped that between the two extremes of their relative movement they will be free from any locking engagement one with the other and when at either extreme of their 80 relative movement they will be locked to each other at the corresponding end of the actuator and free from engagement with each other at the other end of the actuator.

It will be understood that there is a shaft 85 16 for every stop key, and that each shaft is so connected with the corresponding stop key that the shaft and its stop key will rock synchronously whenever rocking movement is imparted either to the stop key by the 90 finger of the organist on said key or by pressure applied to the appropriate actuator B.

Pressure is applied to the actuators to move the corresponding stop keys by a means which includes combination operating elements here shown as a series of slides A, each comprising two members 21 and 22 arranged on opposite sides of all of the shafts 16 and connected with each other for unitary movement, as by the end strips 23 and 24. The 100 number of these slides varies in accordance with the number of different combinations which the instrument is constructed to provide for at any one time. Each slide is suitably pressed resiliently outward, as by 105 means of a spring such as shown at X in Figs. 5 and 7. Each has one of its longitudinal members provided with a series of lateral projections 25 and its other longitudinal member provided with a like series of lateral 110 projections 26. The series of projections 25, and also the series of projections 26, on each slide, correspond in number with the number of shafts 16, and the projections 25 are operatively related to one end of the members 20 of the respective actuators B while the projections 26 are operatively related to the other ends of said members. The 115 cooperative action of the projections and actuators will be hereinafter set forth. In the construction illustrated each slide A is formed of a flat plate and a longitudinal member 27 of greater thickness than the plate: said plate having a longitudinal opening 28 bounded by the members 21 and 22 and end strips 23 and 24 and said longitudinal member 27 being preferably of rounded cross section and fixedly secured to the lower edge of the plate and having end portions or members, 29 (Figs. 5 and 7) and 120

125 130

30, (Figs. 1-4) projecting outwardly in opposite directions therefrom beyond the vertical planes of the ends of the plate. In the illustrated construction the projections 29 of the several slides form bearing elements through which the respective slides have their inner ends supported by inner walls of the chamber in which the action is mounted. Two types of walls are illustrated one, 10 marked D, being pivoted at *d* and applicable to the construction shown in Fig. 5, while the other, marked C, shown in Fig. 7, is fixed and is applicable to the construction shown in Figs. 1-4, inclusive, as well as to the construction shown in Figs. 7 and 8. Each spring X, in all illustrated forms, has one of its free ends connected to the rear end of the corresponding projection 29.

In the operation of preparing a combination, the particular slide A which has been selected to operate the combination is moved inward relatively to the actuators B and to place it in such position that its projections 25 will substantially engage the upper ends 25 of the members 20 of the corresponding actuators. While the parts are in this position, the outer ends of the stop keys corresponding to the particular stops which are to come "on" are pressed downward to their fullest extent, while the outer ends of the stop keys which are to go "off" under control of this slide are pressed upward to their fullest extent, and the outer ends of those keys which are to be "neutral" in this particular combination, are moved to a mid-position. The described movement of the key or keys corresponding to the stop or stops which are to come "on" turns the corresponding shaft or shafts 16 and actuator-members 19 and since the members 20 of said actuators are held against movement at this time by the slide it follows that the lower ends of the actuator-members 19 will be brought into juxtaposition with the lower ends of the actuator-members 20 by this downward movement of the keys. The parts are so correlated that at the end of this movement of the stop key or keys the holding elements *b*, *b'* at the lower ends of the corresponding actuator-members will snap into engagement with each other so as to hold these ends together. The described movement of the key or keys corresponding to the stops which are to go "off" under control of this particular slide, turns the corresponding shaft or shafts 16 and actuating-member or members 19, relatively to the corresponding member or members 20 and causes these members to be locked together 55 at their upper ends instead of at their lower ends: and the described movement of stop key or keys to mid-position places the members of the actuator or actuators corresponding to the keys so moved, in such relation to

each other and to the slide that no movement 65 of the slide will be communicated to said actuators.

By way of concrete examples: let us assume that the organist desires to prepare three different combinations of the stops controlled by the stop-keys marked 10-14, inclusive, in Fig. 1 of the drawing and that in one of these combinations, identified as "first combination", the stops controlled by keys 10 and 12, are to come "on" while the 75 stops controlled by keys 11, 13 and 14 are to go "off" when the particular slide A selected to operate this combination is actuated; while in another combination, identified as "combination No. 2", the stops controlled by keys 10, 11 and 13 are to come "on" 80 and the stops controlled by keys 12 and 14 are to go "off" when the particular slide A selected for this operation is operated; and in still another combination, identified as 85 "combination No. 3," the stop controlled by key 10 is to remain "neutral", while the stops controlled by keys 12 and 14 are to come "on" and the stops controlled by keys 11 and 13 are to go "off": the organist in preparing 90 these combinations, proceeds as follows:

The particular slide which is to operate the "first combination" is moved inward and while it is being held in said position the organist presses the outer ends of stop 95 keys 10 and 12 downward as far as they will go and all other stop keys upward as far as they will go; in preparing "combination No. 2" he similarly presses the outer ends of stop keys 10, 11 and 13 downward and the 100 remaining stop keys upward, while the slide which controls this combination is in its inward position; and in preparing "combination No. 3" he places stop key No. 10 in a mid-position, presses stop keys Nos. 12 105 and 14 downward to their fullest extent and stop keys 11 and 13 upward to their fullest extent, while the selected slide is in its inward position. As already described, in preparing the first combination the members 19 110 and 20 of the actuators corresponding to keys 10 and 12 were locked to each other at their lower ends, while the members 19 and 20 of the actuators corresponding to keys 11, 13 and 14 were locked to each other at 115 their upper ends; and that in preparing combination number 2, the actuators corresponding to keys 10, 11 and 13 have their members 19 and 20 locked to each other at their lower ends, while the similar members of the actuators corresponding to keys 12 and 14 are locked together at their upper ends; and that in preparing combination No. 3 the members of the actuators corresponding to keys 12 and 14 are locked together at their lower ends, the members corresponding to keys 11 and 13 are locked to each other at 120 their upper ends, while the members of the 125

actuators corresponding to key 10 will be free from each other at both ends of said actuator.

Of course, it will be understood that when each combination has been prepared all keys which had been moved from their normal ("off") positions in setting the combination are returned to their said positions, respectively, and the slide which had been selected 10 to operate said combination and which was held inward while the combination was being prepared, is released and thereupon will be returned to its outer position by its spring X.

15 From the foregoing it will be clear that if the particular slide selected to operate or control the "first combination" be thereafter pressed inward it will act upon the lower, locked together, ends of the actuators 20 corresponding to keys 10 and 12 and upon the upper, locked together, ends of the actuators corresponding to keys 11, 13 and 14 in such manner as to cause the stops corresponding to keys 10 and 12 to speak, and 25 the others to discontinue speaking, if they were "on" or to remain "off" if they were already "off," it, of course, being understood that in this operation the keys 10 and 12 are moved to their "on" position and 30 the keys 11, 13 and 14 moved to their "off" position, if "on" at this time, by the co-operative action of the said slide and actuators; and similarly that when in the playing of the organ the particular slide selected 35 to operate or control combination No. 2 is moved inward it will act upon the lower, locked together, ends of the actuators corresponding to keys 10, 11 and 13 in such manner as to bring said keys into "on" position and upon the upper locked together ends of the actuators corresponding to keys 12 and 14 to move them to "off" position; and, finally, that when the slide selected to 40 operate or control combination No. 3 is moved inward by the organist to bring this combination into operation, stop keys 12 and 14 are lowered to "on" position and stop keys 11 and 13 are raised to "off" position, by the co-operative action of said slide and 45 the actuators corresponding to said keys, while the slide will have no effect whatever upon the actuators corresponding to key 10 and hence the stop controlled by said key will remain "on" if already "on" or "off" 50 if it was off at this moment.

The slides A may be severally operated in various ways, or by various means, two typical means being illustrated for exemplary purposes. In one of these means they are 60 operated by force derived from electrically controlled pneumatics which are under control of the organist, one suitable means for this purpose being shown in Figs. 1-4, inclusive. They may, however, be severally 65 operated by force derived from the fingers

of the organist applied in a more direct manner thereto, as shown in Figs. 5-9, inclusive. Moreover, they may be so arranged with relation to other elements that each will have two distinct and well defined phases of movement in the same direction for certain purposes, one for the setting operation and the other for the playing operation, as in the constructions exemplified by Figs. 1-6, inclusive, or the same purposes may be accomplished by providing for additional movements of the stop keys in lieu of the slides, as exemplified by the construction shown in Fig. 8. This two-phase movement, involving a double touch, is not essential to 80 operativeness but is very beneficial, since it overcomes any tendency to "flutter" of those stops which are in neutral position when a combination is operated. Each slide is provided with an operating means individual 85 thereto, and the several operating means are severally controllable by the organist. The several operating and controlling means are alike and hence a description of one will suffice for all.

Referring, first, to the construction shown in Figs. 1-4, inclusive, illustrating a desirable embodiment in which each slide A has two distinct phases of movement in the same direction imparted to it by an operating means therefor which includes an electrically controlled power pneumatic, P, connected to the outer end of the corresponding slide-member 30 and having its inferior in operative relationship, through a port 31, with a wind channel 32 which has communication with a chamber M through a port 33 controlled by two valve members m and n. The valve member m has a port 34 and the valve member n has a port 35. These valve members are slideable relatively to each other and to the port 33, the member n being connected by a rod n' with the movable member of pneumatic P, while the member m is connected by a rod m' with the movable member of a pneumatic Q. The chamber M contains air at atmospheric pressure when the stop controlled by the corresponding slide A is not in any combination, and at other times contains air at pressure above that of the atmosphere, in the arrangement illustrated. Its communication with the atmosphere is through a port 37, duct 38 and port 39. The air at pressure above that of the atmosphere enters the chamber M from a chamber O through a port 40 and the said duct 38 and port 39. The ports 37 and 40 are respectively controlled by valve members 41 and 42 mounted on a common stem 41' operatively connected at one end to a pneumatic 43 whose chamber is marked 43'. The pneumatic Q is at all times subject externally to the tension of the air in the chamber M while internally it is subject at certain times to air at atmospheric 130

pressure introduced thereinto through channels 44 and 45 and a port 46 and at other times to the pressure of the air in the chamber O, which air enters the same through a 5 port 47 and the said channels 45 and 44. These ports 46 and 47 are controlled by a valve 48 mounted on a stem 49 which is operatively related to a pneumatic 50 whose chamber is marked 50'.

10 R and S designate two electro-magnets whose armatures r and s form, or are provided with, valve members. The valve member r operates between and is adapted to close two ports, 51 and 52, alternately; and 15 the valve member s operates between and is adapted to close two ports 53 and 54 alternately. The ports 51 and 53 are atmospheric ports respectively leading to chambers 55 and 56 which are also respectively tapped 20 by the ports 52 and 54. The latter ports are in communication with the pressure chamber O through channels 57 and 57' respectively. Chamber 55 has communication with the chamber 43' of pneumatic 43 25 through channels 68 while other channels, 69, connect chamber 50' of pneumatic 50 with chamber 56. The magnet R is in an electrical circuit which starts from a source of electrical energy, as the battery 58, and 30 traverses, in turn, wire 59, terminals 60 and 60', wire 61, magnet R, and back to the source through wire 62. The magnet S is in an electrical circuit which starts from a source of electrical energy, as the battery 35 63, and traverses, in turn, wire 64, terminals 65 and 65', wire 66, magnet S, and back to the source by way of wire 67. A suitable means for controlling the circuits which in 40 turn control the operation of the corresponding slides A, comprises a plunger T which is preferably spring pressed outward and has its stem so correlated with suitable switches 70 and 71, Fig. 1, for the respective circuits that it will close the circuit which 45 energizes the magnet R when pressed in a certain distance and will close the circuit which energizes the magnet S when pressed in an additional distance.

When the wind system of the organ is 50 under pressure, the controlling or actuating means of every stop which is not "on" has its elements in the position shown in Fig. 2, upon reference to which it will be noticed:

That atmospheric port 46 and pressure 55 port 40 are closed while atmospheric port 37 and pressure port 47 are open. Hence, chamber M will be closed against pressure chamber O and in communication with the atmosphere through port 39, channel 38 and 60 port 37; while the interior of pneumatic Q will be closed against the atmosphere and in communication with pressure chamber O through channels 44 and 45 and port 47. The result, of course, is the expansion of 65 said pneumatic Q and the positioning of

valve members m and n with their ports 34 and 35 in full registration with each other and with port 33 leading to channel 32. This channel now contains air at atmospheric pressure and since the interior of 70 pneumatic P is in open communication with said channel and its exterior is at the same time (and, in fact, always) subject to air at atmospheric pressure it follows that the pressures within and without said pneumatic 75 counterbalance each other. While the pressures are thus counterbalanced the pneumatic is collapsed and held in collapsed condition, as by a suitable spring, as usual, aided if necessary by the spring X which resiliently presses the corresponding slide A outward. The corresponding slide, therefore, is in its outer position. At this time, of course, the magnets R and S are deenergized.

80 The procedure in setting the mechanism in the preparation of a combination is as follows:—

The organist presses inward to its fullest extent the particular plunger T which he has 90 selected as the one to control the combination being made. This plunger in its inward movement closes the circuits through the magnets R and S and thereby energizes said magnets. The energizing of magnet R 95 causes it to attract its armature r and thereby opens the atmospheric port 51 and closes the pressure port 52 of chamber 55. Communication of chamber 43' of pouch pneumatic 43 with pressure chamber O is thus 100 cut off and at the same time said chamber 43' is opened to the atmosphere through port 51, chamber 55 and channel 68. This results in the deflation of the pneumatic 43 by the preponderating pressure in chamber O, 105 and this deflation causes movement of valve members 41 and 42 and the closing of atmospheric port 37 and opening of pressure port 40; thereby placing chamber M in communication with pressure chamber O. As soon as 110 communication of chamber M with pressure chamber O is established there will be an inrush of air under pressure above that of the atmosphere from said chamber M into channel 32, through the fully registered ports 34, 35 and 32. The particular power pneumatic P connected with said channel 32 is thus subjected to internal pressure sufficiently strong to inflate it. As it becomes inflated outward 115 movement of its movable member draws with it the valve member n and thereby positions the port 35 in said valve member out of registration with port 34 of valve member m, and thus cuts off communication between the chamber M and the interior of the power pneumatic P. This completes the first 120 phase of inward movement of the slide A, it being, of course, understood that the inflation of said pneumatic caused it correspondingly to move the particular slide A to which 125 130

it is connected. The parts are now in the position shown in Fig. 3.

The admission into chamber M of air at pressure above that of the atmosphere also resulted in a counterbalancing of the internal and external pressures to which the pneumatic Q is subjected, since the interior of said pneumatic is still in communication with pressure chamber O, through channels 44 and 45 and port 47. It will be remembered, however, that in the setting operation the plunger T is pushed inward to its fullest extent and, therefore, that the circuit through magnet S is closed at the end of the inward movement of said plunger. The closing of the circuit through this magnet opens the corresponding atmospheric port 53 and closes the corresponding pressure port 54, thereby closing the corresponding chamber 50' of pouch pneumatic 50 against pressure chamber O and opening it to the atmosphere. The pressure in chamber O will thereupon become effective upon said pneumatic to cause movement of the valve 48 to open atmospheric port 46 and close pressure port 47 of the corresponding chamber 56. The interior of pneumatic Q is thus cut off from communication with pressure chamber O and is vented to the atmosphere, whereupon the pressure in chamber M, which of course is still in communication with pressure chamber O, becomes effective to collapse said pneumatic, with the result that valve member m is moved, relatively to valve member n, to a position which re-establishes communication of chamber M with chamber 32, through the ports 34, 35 and 33. This results in an additional expansion of pneumatic P and, in consequence, the second phase of inward movement of the corresponding slide A. The parts are now in the position shown in Fig. 4.

The correlation of the parts is such that both phases of inward movement of the slide are brought about in the setting operation while its first phase of movement only is accomplished in the playing operation. In other words, in the setting operation both magnets R and S are energized by the pushing inward of the plunger T to the extent which closes both circuits, while in the playing operation—i. e. to bring the set combination into operation—the magnet R only is operated.

When the setting operation has been completed the circuits which energized the magnets R and S, respectively, are broken by the withdrawal of the corresponding plunger T. The de-energization of magnet S closes atmospheric port 53 and opens pressure port 54, thereby placing chamber 50' of pouch pneumatic 50 under pressure equal to that in chamber O, whereupon valve 48 will close atmospheric port 46 and open

pressure port 47, thus increasing the pressure of the air in the interior of pneumatic Q to the same as that in chamber O. The de-energization of magnet R, which obviously occurs immediately after the de-energization of magnet S, causes the atmospheric port 53 to be closed and the pressure port 54 to be opened, thereby placing chamber 43' of pouch pneumatic 43 in communication with pressure chamber O.

This results in movement of valve members 42 and 41 to close pressure port 40 and open atmospheric port 37, respectively. Hence, communication of chamber M with pressure chamber O is cut off and said chamber M is vented to the atmosphere. Chamber M and pneumatic P now contain air at atmospheric pressure and pneumatic Q contains air at pressure above that of the atmosphere. The preponderating pressure in the pneumatic Q causes the expansion of said pneumatic, while the counterbalancing of pressures within and without the pneumatic P permits the spring or springs which are operatively related to said pneumatic to become effective to deflate the same. The expansion of pneumatic Q moves the valve member m toward the right and the deflation of pneumatic P moves the valve member n similarly toward the right, thus restoring the parts to the position originally occupied by them (shown in Fig. 2) ready to bring "on" the combination predetermined by the setting operation, whenever the circuit is closed through the magnet R without being closed through the magnet S.

It will be understood that springs or the like may be provided wherever necessary or desirable to operate or assist in the operation of any of the pneumatics in one direction.

It is to be observed that the valve member m has a depression 34' in its upper face and that the valve member n has an opening 36 in registration with said depression. This depression and opening are in communication with the atmosphere through a channel 36'. By means of this connection to the atmosphere a slight pressure is maintained upon the valve members operative to hold them in place whenever conditions of pressure exist in the chamber M.

Figs. 5, 6, 7, 8 and 9 illustrate a means for operating each slide A without the intervention of power pneumatics or electrical controls. This means comprises a plunger 100 for each slide, connected with the latter by a bell crank lever, one arm (101) of which is pivoted to the inner end of a projection 100' from the plunger, and the other arm (102) of which is pivoted to one end of an arm 103 whose other end is pivoted, at 104 to an end of the corresponding slide A. Each bell crank lever is pivoted at 105 to an appropriate part of the organ structure.

These figures illustrate constructions which are alike in respect of the means last described but differ in respect of the means they disclose for permitting a setting of any 5 of the stops in neutral position.

In the construction shown best in Figs. 5 and 6 the capability of the setting of the parts into the referred to neutral position without any liability of any fluttering of the 10 stops corresponding to actuators which are in a neutral setting when the combinations including said actuators are operated, is made possible by providing in the setting operation for an extent of travel of each 15 slide additional to that thereafter required into bringing the stops into "on" or "off" condition, being in this broad respect the construction shown in Figs. 1-4, inclusive; but since the electrical controls and power 20 pneumatics co-operating in the construction shown in Figs. 1-4 to move the slides are not employed and since means should be employed to define the phases of inward movement of the slides, when such movements are 25 contemplated, there may be employed for the latter purpose, a stop means, such as the hereinbefore wall D resiliently pressed forward, by a spring or springs 201, into the path of rearward movement of the slide. 30 The correlation of the slide and stop is such that when the slide and stop are both in their forward positions, they will be separated a distance which permits the slide to traverse its first phase of inward movement 35 in the setting operation, before it comes into contact with the stop, the second phase of inward movement of the slide then requiring greater force to overcome the tension of the spring or springs (201). This wall thus defines the inner end of the first phase of inward movement of the slide and indicates when said movement has been completed, for convenience of the organist in operating the combination which has been set to be controlled by said slide. 45 In the particular construction exemplifying this form of the invention, the stop D is pivoted at its upper end, (at d) and the inner end of the slide member 28 has a shoulder 203 to engage the stop. 50 There may be one stop common to all the slides, or a separate stop for each slide, as desired. In other words, the stop may be a continuous member, different portions of whose length are in operative relation 55 with the slides respectively, or in lieu of such continuous member, there may be employed a series of independently movable stops for the series of independently movable slides, respectively. 60 Figs. 8 and 9 exemplify a construction in which the resilient stop means operates upon the stop keys. In this construction the opening 300 through which the finger portion of the stop key projects is provided 65 above and below said portion with resilient

fingers 301 and 302, respectively so correlated with the stop key and opening 300 that they will define the normal movement of the stop key i. e. the movement of the stop keys from or into its "off" position, 70 while permitting additional movement of said key in the setting operation. It will be noticed in this connection that the opening 300 is enlarged at opposite sides of the stop key and contiguous to the outer portions of the fingers, as shown at 303 and 304, respectively, and have channels 305 and 306 which receive the bent free outer ends of said fingers when the key is pressed up or down beyond its before mentioned normal travel. Of course, it will be understood that there is one pair of these spring fingers for every stop key. It will be noted that this embodiment typifies a construction in which the two phases of movement are of 85 the stop keys instead of the slides.

Whether the two phases of movement are in the stop keys or in the slides, it is apparent that these movements are relative between the slides and stop keys. It should 90 also be understood that the terms inward or outward, upper and lower, atmospheric pressure and pressure above that of the atmosphere are employed herein in an illustrative sense and not with a purpose of 95 restricting the invention to the particular arrangements of parts shown or to the use of the particular pressures named. It will also be understood that the constructions illustrated are merely exemplary and that the 100 details may be changed and the invention otherwise and variously embodied without departing from its spirit or the scope of appended claims. For example: (1) the combination slides may be operated, when 105 a motor is used, by one master motor instead of by small individual motors, and (2) the work done by the second touch applied to the plunger may be accomplished by using a single additional plunger or stop 110 key, operative to control the second movement of the master motor, for instance. Finally, it will be understood that in certain instances it may not be impracticable to employ the actuators herein described 115 without means of the broad or specific character herein set forth for setting them, as they may be set directly by hand, instead of by the stop keys, or conjoint action of stop keys and combination operating elements, although the advantages of the setting of the actuators without having to enter or to reach into the interior of the organ 120 will be apparent.

Having now described the invention and 125 set forth certain typical embodiments thereof of what I believe to be new and desire to secure by Letters Patent, is:—

1. A combination stop mechanism for organs or the like comprising elements each 130

settable into an "on" position, an "off" position or a "neutral" position, a combination setting and operating element and an element movable relatively to the said setting and operating element and co-operating therewith to set the first named elements into any of their said positions.

2. A combination stop mechanism for organs or the like, comprising actuators settable into "on" position, "off" position or "neutral" position, and relatively movable means co-operatively operative to set any of the actuators into any of the aforesaid positions, one of the said means being also operative with relation to the actuators which have been set to "on" or "off" position to move the other means accordingly and inoperative with relation to those actuators which are set to "neutral" position.

20 3. A combination stop mechanism for organs or the like, comprising actuators settable into "on" position, "off" position, or "neutral" position, and stop keys and combination operating elements co-operatively operative to set any of said actuators into position in which the corresponding stop will come on or go off under control of the combination operating elements or be unaffected by the operation of the latter.

30 4. A combination stop mechanism for organs or the like, comprising actuators settable into "on" position, "off" position, or "neutral" position, and stop keys and combination operating elements, conjointly operative with relation to said actuators to set any of the latter into positions to cause the stop keys to be moved to "on" or "off" position under control of the combination operating elements, in accordance with the settings of the actuators, the stop keys being also operative to set any of the actuators into position with relation to the combination operating elements to be inoperative thereby.

45 5. A combination stop mechanism for organs or the like, comprising stop keys, combination operating elements and connections including reversibly operative actuators settable by the conjoint operation of said stop keys and combination operating elements and when so set are operative to move the stop keys onto "on" or "off" position under control of said operating elements and also settable to "neutral" position so as to be unaffected by the operation of said elements.

60 6. In a combination stop mechanism for organs or the like, a plurality of reversibly operative actuators each comprising a plurality of members movable together in the operation of the combination and relatively to each other into a position to render the actuator inoperative in either direction.

65 7. In a combination stop mechanism for organs or the like, a series of actuators each comprising a plurality of relatively movable

members releasably securable to each other at either end of the actuator, to render the actuator reversibly operative, said members also being relatively settable to an intermediate position, to render the actuator inoperative in either direction.

70 8. In a combination stop mechanism for organs or the like, a plurality of shafts, a plurality of actuators on each of the same, each actuator comprising a member fixed to the corresponding shaft and a complementary member supported by the shaft and movable relatively thereto, said members correlated to be releasably securable to each other at either end, to render the actuator reversibly operative, and settable to an intermediate position to be inoperative in either direction.

75 9. In a combination stop mechanism for organs or the like, a plurality of shafts, a plurality of actuators on each of the same, each actuator comprising a member fixed to the corresponding shaft and a complementary member supported by the shaft and movable relatively thereto, said members correlated to be releasably securable to each other at either end, to render the actuator reversibly operative, and settable to an intermediate position to be inoperative in either direction, and setting and operating 85 means operatively connected to said actuators.

90 10. In a combination stop mechanism for organs or the like, a plurality of shafts, a plurality of actuators on each of the same, each actuator comprising a member fixed to the corresponding shaft and a complementary member supported by the shaft and movable relatively thereto, said members correlated to be releasably securable to each other at either end, to render the actuator reversibly operative, and settable to an intermediate position to be inoperative in either direction, and setting and operating 95 means including stop keys operatively connected to said shafts and operating elements movable relatively to the shafts and having members engageable with the ends of the actuators.

100 11. A combination stop mechanism for organs or the like, comprising reversibly operative actuators, respectively also settable to neutral position, and setting and operating means operatively connected with each actuator and including elements which have relative movement for the setting operation and move together for the playing operation and whose extent of relative movement in the setting operation is different from that of their movement together for the playing operation.

115 12. A combination stop mechanism for organs or the like, comprising reversibly operative actuators, respectively settable also to a neutral position, and relatively movable 120

setting and operating elements operatively connected with each actuator, one of said elements having an extent of movement in the setting operation greater than that for the playing operation.

13. A combination stop mechanism for organs or the like, comprising reversibly operative actuators, respectively settable also to neutral position, stop keys and combination operating elements movable relatively in the setting operation and together in the playing operation and each operatively connected with the actuators, said keys and operating elements having for the setting operation a relative movement whose length is greater than that traversed by them in the playing operation.

14. A combination stop mechanism for organs and the like, comprising actuators settable into "on" position, "off" position or "neutral" position, and combination operating elements having members engageable with the actuators for the playing operation, each combination operating element being movable relatively to the corresponding actuators in the setting operation and having in said operation a greater extent of movement than the distance traversed by it in the playing operation.

15. A combination stop mechanism for organs and the like, comprising actuators settable into "on" position, "off" position or "neutral" position, setting means including stop keys having connection with the actuators and combination operating elements having members engageable with corresponding actuators, said combination operating elements being movable relatively to the actuators and stop keys in the setting operation and being operative to move said actuators and stop keys in the playing operation and having in the setting operation a movement of greater length than in the playing operation.

16. A combination stop mechanism for organs or the like, comprising combination setting and operating means, including combination operating elements and electrically controlled means respectively operative to move said elements through two phases in the setting operation and one of said phases in the playing operation.

17. A combination stop mechanism for organs or the like, comprising combination setting and operating means, including combination operating elements and electrically controlled means respectively operative to move said elements and each including a plurality of successively controllable circuits and connections between the same and the corresponding combination operating element operative to move the latter varying distances according to the number of the circuits closed.

18. A combination stop mechanism for or-

gans or the like, comprising actuators settable into "on" position, "off" position or "neutral" position, combination operating elements having members engageable with the actuators for the playing operation, each combination operating element being movable relatively to the corresponding actuators in the setting operation, power pneumatics connected to the respective combination operating elements and electrically controlled control means for said power pneumatics, respectively, each control means including a plurality of circuits and operative connections to the corresponding power pneumatic to cause the latter to move the combination operating element a greater distance in the setting operation than in the playing operation.

19. In a combination stop mechanism for organs and the like, settable actuators and setting and operating means, operative with relation to said actuators and including combination operating elements, a power pneumatic for each operating element, and control means for each power pneumatic, each control means having a plurality of relatively movable ported valves one of which is operated by the power pneumatic, a second pneumatic to operate the other valve, said valves conjointly controlling the air tensions within the power pneumatic, pneumatically operable valves to control the air tensions to which the second pneumatic is subjected and electrically controlled control means for the latter valves, including a plurality of successively controllable circuits both of which are closed in the setting operation and only one of which is closed in the playing operation.

20. A combination stop mechanism for organs or the like comprising actuating elements each settable into an "on" position, an "off" position or a "neutral" position, a slideable combination setting and operating element having members to engage said actuating elements in its combination-setting and combination-operating movements, an operator-controlled means to operate said slideable element in one direction in the setting operation and for the playing operation, means to move said slideable element in the opposite direction at the ends of the setting and playing operations, and an element movable relatively to the combination setting and operating element and co-operating therewith in the setting of the combination.

21. A combination stop mechanism for organs or the like comprising actuating elements each settable into an "on" position, an "off" position or a "neutral" position, a slideable combination setting and operating element having members to engage said actuating elements in its combination-setting and combination-operating movements, an operator-controlled means to operate said

slidable element in one direction in the setting operation and for the playing operation, means to move said slidable element in the opposite direction at the ends of the 5 setting and playing operations, and an element movable relatively to the combination setting and operating element and co-operating therewith in the setting of the combination and movable with said combination setting and operating element in the operation 10 of the combination.

22. A combination stop mechanism for organs or the like, comprising actuating elements each including a plurality of relatively movable members having means to releasably secure them together at either end 15 of the actuator, and relatively movable means co-operating with each other to move the actuator-members into positions to cause 20 their locking means to interengage at the selected ends of the actuators.

23. A combination stop mechanism for organs or the like, comprising actuating elements each including a plurality of relatively movable members having means to releasably secure them together at either end 25 of the actuator, slidable members operative in the setting operation to hold corresponding members of the actuators against move-

ment, and stop keys operative in the setting 30 operation in opposite directions to move the other members of the actuators into position to interlock with the held members of the actuators at one end or the other of the latter according to the direction of movement of 35 the stop keys.

24. A combination stop mechanism for organs or the like, comprising actuating elements each including a plurality of relatively movable members having means to 40 releasably secure them together at either end of the actuator, slidable members operative in the setting operation to hold corresponding members of the actuators against movement, stop keys operative in the setting 45 operation in opposite directions to move the other members of the actuators into position to interlock with the held members of the actuators at one end or the other of the latter according to the direction of movement of 50 the stop keys, and operator-controlled means to operate upon said slidable members to control the stops in accordance with the combinations set by the conjoint operations of said slidable members and keys in the 55 setting operation.

In testimony whereof I affix my signature.
FREDERICK J. FLAHERTY.
